LET-OFF FOR LOOMS

Application filed June 21, 1928. Serial No. 287,336.

The invention has relation to positive let-offs of the class in which the action of the let-off mechanism of a loom in producing warp-delivering rotation of a warp-beam is governed by the tension of that portion of the warp extending forward through the loom toward the active weaving instrumentalities.

The invention consists in a let-off mechanism of novel and improved construction intended to meet all the requirements known to me to be essential for good weaving.

The constructional details of a let-off embodying the principles of the invention admit of being varied in practice.

Two illustrative embodiments of the said principles are shown in the accompanying drawings, in which latter—

Fig. 1 is a view showing one of the said embodiments in side elevation, partly in section. In this view the let-off mechanism is represented as employed in connection with the right-hand side of a loom.

Fig. 2 is a view thereof in rear elevation.

Fig. 3 is a partly sectional view of certain elements, shown detached from the general mechanism.

Fig. 4 is a side elevation showing an embodiment providing for adjustment of the transmission-gear assembly to suit warp-beams of different length. In this view the let-off mechanism is represented as employed in connection with the left-hand side of a loom.

Fig. 5 is a rear elevation view of portions of this second embodiment.

Figs. 6 and 7 are views in side elevation and rear elevation, respectively, of the adjustable warp-beam support of Figs. 4 and 5.

Referring first to Figs. 1 and 2 of the drawings, these views show a portion of one side-frame 1 of a loom. They show, also, a portion of the loom crankshaft 2, mounted in a bearing on said side-frame, and a hand-wheel 3 on said crankshaft. They show also a bracket 4 projecting rearward from the said side-frame and provided with an open slotted bearing 5 receiving a journal 6 of a warp-beam 7; in addition, they show a bracket 8 attached by means of bolts 9, 9, to the bracket 4, projecting rearward therefrom, and sup-

porting a back-bearer 10 to which the warp 11 passes from the warp-beam 7. The said back-bearer constitutes a definitely-located warp-guiding support from which the warp extends forwardly in the loom to the harnesses and other active weaving instrumentalities. It preferably consists of a roll which is journaled in a bearing provided in connection with the bracket 8. The beam-journal 6 is shown as held in place within the slotted bearing 5 and in contact with the closed inner end thereof by means of an end-cap 12, shown engaged with the outer end of the said journal and fastened to the outer side of bracket 8 by means of one of the bolts 9 and its nut.

The warp-beam 7 is combined operatively with the let-off ratchet-wheel 16 by means of a transmission gear-assembly comprising, in the drawings, a worm-gear 13 that is coupled with the said warp-beam, a worm 14 that engages the said worm-gear, and intermeshing bevel-gears 15, 151, constituting driving connections between the shaft 161 of the ratchet-wheel 16 and the shaft 141 of the said worm.

The means for actuating the ratchet-wheel 16 and the associated train (just described) for the purpose of turning the warp-beam to unwind warp therefrom, comprises a pawl 17 which engages the teeth of ratchet-wheel 16, a swinging pawl-carrier 18, a spring 19 for moving the said pawl-carrier backward to retract the pawl relative to the teeth of the ratchet-wheel into a fresh starting position, and a rod 20, having a reciprocatory endwise movement imparted to it, in this instance by means of a crank 21 on the loom crankshaft 2, although the precise actuating means is not material, the said rod being provided with a collar 22 designed to engage with the pawl-carrier in the stroke of said rod in one direction, so that when such engagement takes place the pawl-carrier is actuated to move the pawl forward from its starting position so as to turn the ratchet-wheel to produce a turning movement of the warp-beam for warp-delivery purposes.

As a convenient feature of construction, the pawl-carrier 18 is sleeved upon the shaft 100

161 of ratchet-wheel 16, so that it swings concentrically with the said ratchet-wheel. The pawl 17 is carried by one arm of the swinging pawl-carrier, while the other arm has a hole therethrough which is occupied by the actuating rod 20. By reason of this relationship of the rod and pawl-carrier the rod is guided in its movements, and proper coaction between the rod and pawl-carrier is ensured.

10 Briefly summarized, spring 19 provides for actuation of the pawl-carrier and pawl with yeilding force for the return movement of the pawl-carrier and pawl toward starting position; the reciprocating rod 20 and its collar 22 provide for positive actuation of the pawl-carrier and pawl from starting position in the direction for producing rotation of ratchet-wheel 16 in the direction for occasioning rotation of the warp-beam for warp-delivery.

15 In accordance with the invention, for governing the action of the let-off mechanism by the tension of that portion of the warp extending from the warp-beam and forward through the loom, I employ a tension-controlled member between which and such portion of the warp there is interengagement. Such tension-controlled member is or may be 20 of the same general character as the whip-rolls which have been employed heretofore in other mechanisms of the same class of let-offs. The said tension-controlled member is combined operatively with the pawl-carrier 25, 18 in manner to control the extent of the return stroke of the said pawl-carrier and the pawl 17 after a feed-movement thereof; with a view, in particular, to varying the starting position of the pawl so as to cause the extent 30 of every feed-movement that is imparted to the pawl to be proportioned according to the state of tension of the said portion of the warp at the time of such feed-movement.

35 In the preferred mode of reducing of the invention to practice the said tension-controlled member (whip-roll) is combined operatively with the pawl-carrier for the purpose stated by means of a pawl-carrier stop, the position of which is determined through 40 the position assumed by the whip-roll under the control of the warp-tension.

45 The whip-roll shown in the drawings comprises a warp-engaging member constituted by a roll 23, supporting arms 24, and a rock-shaft 25 journaled in bearings in connection with stands 251, mounted upon the brackets 4.

50 The whip-roll is backed-up against the pressure of the warp by means of an expanding spiral spring 30 acting against an arm 31 fixed upon the rockshaft 25 of the whip-roll. This spring acts with a tendency to rock the whip-roll so as to take up any slack in the portion of warp extending from the warp-beam and forward through the loom, and so as to maintain such portion in a con-

stant state of tension. Excess movement under the action of spring 30 is prevented by contact of the back of the said arm 31 with a stop constituted by a washer and nut 32 upon a rod 33 extending from a fixed arm 34 projecting from bracket 4. The spring surrounds the said rod between the said arm and an abutment 35 sleeved upon the rod adjacent the fixed arm 34. The position of stop 32 may be varied, so as to vary the height capable of being assumed by the roll 23, as for varying the height of the sheet of warp at and forward of such roll, through adjustment of the said stop 32 upon rod 33 in the direction of the length of such rod, or by adjustment of the nut or nuts 36, applied to the opposite end of the rod 33 for the purpose of holding the rod in place in connection with the fixed supporting arm 34. These adjustment-means also enable the tension of the spring 30 to be varied.

55 In this instance the pawl-carrier stop 28, Fig. 3, is constituted by a stop-collar 28 upon a rod 27, such collar serving, as the case may be, either to prevent the pawl-carrier from making a return-movement relative to the teeth of ratchet-wheel 16, or to permitting a return-movement of the pawl-carrier through the action of spring 19 to an extent determined by the state of tension of the warp. Through the whip-roll and connections to the pawl-carrier stop, the state of tension of the warp determines the position of the said stop 28, and thereby determines whether the pawl-carrier and pawl shall make a return-movement to a starting position for a fresh warp-delivering feed-movement; and through determining also the extent of return-movement determines the location of the starting position for the next feed-movement of the pawl. Thus, according to the said state of tension either warp-delivery is suspended or the extent of turning movement communicated to the ratchet-wheel 16 and the warp-beam by the pawl 17 in its ensuing advance is proportioned suitably to meet the requirements of the moment. The whip-roll is connected to the stop by means of an arm 26 extending from the rockshaft 25 and having engaged pivotally therewith the upper end of the rod 27, the lower end of which extends through a hole provided in the pawl-carrier alongside that occupied by actuating rod 20. The end of spring 19 opposite from the end engaged with the pawl-lever is engaged in the present instance with a collar 29 that is adjustable upon the rod 27 lengthwise of such rod, such collar serving as a convenient point of attachment for such end of the spring.

60 En résumé:

65 In operation, the guide or roll 23 of the whip-roll not only determines the height of the sheet of warp extending forwardly through the loom-harnesses and reed toward

the loom breast-beam, but being subjected to pressure due to the tension of such sheet of warp is affected more or less as to its own position by such tension. Changes in the position of the whip-roll are accompanied by changes in the position of pawl-carrier stop 28, either suspending a return-movement of the pawl-carrier and pawl after a feed-movement thereof, or resulting in corresponding variations in the extent of the return movements of the pawl-carrier and pawl after forward feed-movements thereof, and consequently modifying the extent of the ensuing feed-movements and the rate of warp-delivery.

The employment of a back-bearer constituted by a guide or roll, as 10, intermediate the warp-beam and the whip-roll prevents the angle of incidence of the warp upon the whip-roll from being altered through decrease in the diameter of the wound yarn-mass carried by the warp-beam. Consequently, by reason of the line of pull of the warp at the whip-roll remaining unchanged from first to last, the inter-action between the warp and the whip-roll is unaffected by differences in the diameter of the yarn-mass upon the beam. In ordinary practice with other forms of let-off mechanisms, it usually is necessary to make one or more adjustments as the warp is paid off from the warp beam, in order to compensate for the reduction of the warp-diameter.

In the embodiment of the principles of the invention that is illustrated in Figs. 4 to 7, the brackets 4 and 8 of Figs. 1 and 2 are replaced by a stand 41 and a bracket 42. Stand 41 is attached by means of bolts 91, 91, to the loom-side 1 and a main web-portion thereof extends from said loom-side inwardly crosswise of the loom. The said web-portion is slotted as at 411, 411, Fig. 5, transversely of the loom to permit of adjustment of bracket 42 thereon in the direction of the width of the loom. The foot-portion of bracket 42 is fixed against the rear face of the said web of stand 41 by means of bolts 43, 43, occupying the slots 411, 411. Such slots provide for said adjustment of bracket 42 transversely of the loom. The shaft 141 of the let-off worm 14 is journaled in bearings in a small stand 142 that is affixed against the inner side of bracket 42 by means of a bolt 143 occupying a slot 144, Fig. 6, in the bracket 42. By means of this small bearing stand the worm-shaft and worm are supported in working relations with worm-gear 13 of the warp-beam. The slot 144 in bracket 42 permits the worm-shaft and worm to be adjusted toward and from the axis of the warp-beam, to suit the diameter of worm-gear 13, so as to enable the thread of the worm to be placed properly in mesh with the teeth of the worm-gear. Bevel-gear 15 is mounted on the transversely-extending

let-off shaft 161 between the bevel-gear 151 of the worm-shaft and the flat web of bearing-bracket 142. For the purpose of causing the bevel-gear 15 to rotate in unison with the let-off shaft, while providing for shift of such bevel-gear lengthwise of the let-off shaft into different working positions, a longitudinally extending spline or groove 145, Fig. 5, is provided in connection with the let-off shaft.

As will be perceived, the described construction permits bracket 42 and its bearing for the corresponding journal of a warp-beam to be adjusted transversely of the loom into a position to suit the length of warp-beam desired to be used; and provides also for adjustment in company therewith of the assembly of gearing providing for transmission of motion from the let-off shaft to the warp-beam for letting-off purposes.

In order to enable the warp-beam to be turned manually by a weaver or loom-fixer, as for the purpose of paying-out warp therefrom, or rewinding it thereon, I may provide for the removable application of a crank-handle, as 162, Fig. 2, to the outer end of shaft 161. In this instance the said shaft-end is squared, to fit a square socket in the crank-handle.

What is claimed as the invention is:—

1. In a loom, let-off mechanism comprising a ratchet-wheel and mechanism connected therewith for imparting turning movement to a warp-beam for delivering warp therefrom, an actuating pawl and a pawl-carrier, means for yieldingly restoring said pawl-carrier and pawl to starting position, means for actuating said pawl-carrier and pawl from such position to rotate the ratchet-wheel, a back-bearer to which the warp passes on its way from the warp-beam and around which the warp changes direction in going to the weaving instrumentalities of the loom, a spring-actuated warp-engaging member located toward the front of the loom relative to the said back-bearer controlled as to its position by the warp-tension, and a rockshaft mounted in advance of the said roll and from which arms extend rearwardly for the support of the said warp-engaging member and another arm extends downwardly and has connected therewith means through which the said starting position is determined conformably with the position assumed by the said member under the control of the warp-tension.

2. Loom whip-roll devices comprising a rockshaft, arms projecting rearwardly from said rockshaft, a warp-engaging member carried by said arms and receiving the pressure of the warp on its way to the weaving instrumentalities, an arm affixed to the said rockshaft, a rod, an expansion spring surrounding said rod and acting against said arm to swing the whip-roll in opposition to the pressure of the warp, and adjustment

means for varying the tension of said spring.

3. Loom whip-roll devices comprising a rockshaft, arms projecting rearwardly from said rockshaft, a warp-engaging member carried by said arms and receiving the pressure of the warp on its way to the weaving instrumentalities, an arm affixed to the said rockshaft, a rod having thereon a stop which limits the extent of the swing of the said arm, an expansion spring surrounding said rod and acting against said arm to swing the whip-roll in opposition to the pressure of the warp, and adjustment means for varying the tension of said spring.

15 4. Loom let-off mechanism comprising, in combination, a let-off shaft extending transversely of a loom, means for actuating said shaft for letting-off purposes, a warp-beam support adjustable transversely of the loom 20 to suit the length of the warp-beam placed in the loom, and gearing by which movement is transmitted from the said let-off shaft to the beam to unwind the warp from the latter as required in the weaving, said gearing adjustable with said support lengthwise of the shaft and relative thereto.

5. Loom let-off mechanism comprising, in combination, a let-off shaft extending transversely of a loom, means for actuating said 30 shaft for letting-off purposes, a warp-beam support adjustable transversely of the loom to suit the length of the warp-beam placed in the loom, and means for transmitting rotation to the warp-beam from the let-off shaft, 35 comprising a wheel engaged with such shaft to turn in unison therewith and adjustable lengthwise on the shaft as the warp-beam support is adjusted, and a transmission-gearing assembly connecting said wheel with the 40 warp-beam and carried by the said support.

6. Loom let-off mechanism comprising a warp-beam, a worm-gear operatively combined therewith, a worm engaging with said worm gear, a ratchet-wheel combined with 45 said worm, an actuating pawl, a pawl-carrier, means for yieldingly urging said pawl-carrier and pawl toward starting position, a yieldingly-actuated whip-roll, a longitudinally-movable rod operatively combined with 50 the whip-roll and carrying a pawl-carrier stop which defines the starting position of the pawl-carrier and pawl, and a reciprocating rod having means for engaging said pawl-carrier in movement of the rod in one direction, to cause the pawl to advance the ratchet-wheel and warp-beam for the delivery of warp.

7. In loom let-off mechanism comprising a warp-beam-actuating ratchet-wheel, an actuating pawl, a pawl-carrier, means for yieldingly urging said pawl-carrier and pawl reversely toward starting position, a yieldingly-actuated whip-roll, and a whip-roll arm, the combination with the said elements, of a longitudinally-movable rod connected with said

70 whip-roll arm and carrying a shoulder for engagement with the pawl-carrier to define the said starting position, and a reciprocating rod equipped for engaging said pawl-carrier in movement of the rod in one direction and thereby actuating the pawl-carrier from said starting position so as to produce unwinding rotation of the warp-beam, both rods guided by the pawl-carrier in their reciprocation movements.

75 8. Loom-let-off mechanism comprising a loom shaft, a crank combined therewith, a warp-beam, a worm gear combined therewith, a worm engaging with said worm gear, a ratchet-wheel combined with said worm, an actuating pawl, a pawl-carrier, a yieldingly-actuated whip-roll, a longitudinally-movable rod combined with the whip-roll and having a pawl-carrier stop which defines the starting position of the pawl-carrier and pawl, a rod 80 connected with and reciprocated by the crank aforesaid and having means for engaging the pawl-carrier in movement of the rod in one direction, to cause the pawl to advance the ratchet-wheel and warp-beam for the delivery of warp, and a spring connecting the pawl-carrier with the said rod to urge the pawl-carrier and pawl yieldingly toward starting position.
